Primary Examiner — Mark Booker(74) *Attorney, Agent, or Firm* — Eric E. Silverman(57) **CLAIM**

The ornamental design for a dispenser, as shown and described.

DESCRIPTION

FIG. 1 is a perspective view showing a new design for a dispenser;

FIG. 2 is a top view thereof;

FIG. 3 is a front view thereof, a rear view being a mirror image thereof;

FIG. 4 is a right side view thereof;

FIG. 5 is a left side view thereof;

FIG. 6 is a bottom view thereof; and,

FIG. 7 is a perspective view thereof showing the dispenser with a note.

The portions of the dispenser in FIGS. 1-4, 6, and 7 shown in broken lines are included to show features that form no part of the claimed design.
